UNITED STATES PATENT OFFICE.

ARTHUR C. HOPKINS, OF NILES, MICHIGAN, ASSIGNOR TO NATIONAL STANDARD COMPANY, OF NILES, MICHIGAN, A CORPORATION OF MICHIGAN.

CARRIER FOR BRAIDING MACHINES.

Application filed April 18, 1924. Serial No. 707,395.

To all whom it may concern:

Be it known that I, ARTHUR C. HOPKINS, a citizen of the United States, residing at Niles, in the county of Berrien and State of Michigan, have invented a new and useful Improvement in Carriers for Braiding Machines, of which the following is a specification.

This invention relates to carriers for 10 braiding machines and the like and is fully described in the following specification and shown in the accompanying drawings in which:

Figure 1 is a side elevation of a carrier 15 embodying the invention;

Fig. 2 is a rear elevation of the same; and

Fig. 3 is a partial horizontal section on the line 3 of Fig. 2.

The embodiment illustrated comprises a 20 carrier for braiding machines of a well known type, said carrier having a base 10 from which rises standards 11 and 12. A brake drum 13 has a circular hub 14 which 25 is journalled in the standard 11.

A squared central opening 15 is provided in the brake drum 13 which is adapted to receive the square pin 16, the rounded opposite end 17 of which is journalled in the 30 standard 12. This pin is adapted to carry a spool 18 which has a square central opening therein so that when assembled as shown in Fig. 3, the drum 13 and spool 18 are locked together.

Wire 19 to be fed by the carrier is wound 35 upon spools 18 and one of these inserted in the carrier. This wire passes up over the sheave 20 under the sheave 21 over the sheave 22 and out through the eyelet 23 to 40 the braiding machine or to the other device to which the wire is to be fed.

The sheaves 20 and 22 are journalled on pins 24 and 25 which are carried by the 45 standards, while the sheave 21 is journalled on the outer end of a lever arm 26 which is pivotally mounted at 27 and is normally pressed outwardly toward the dotted line position of Fig. 1, by means of a compression spring 28 acting upon the opposite end 50 26^a of the lever arm 26 as shown in Fig. 2.

This end 26^a, when the lever arm is drawn inwardly to the full line position shown in Fig. 1, is adapted to engage the outer end 55 of the lever 29 which is fulcrumed at 30 and carries a pin 21 on which is pivotally

mounted a brake shoe 32 of hard fibre or the like which is adapted to bear upon the groove 13^a of the brake drum 13.

The operation of this braiding carrier is as follows: During the braiding operation, 60 the braiding carrier moves toward and from the braiding machine with an oscillatory motion which necessitates that some means be provided for taking up the slack in the wire 19 as the carrier moves toward 65 the braiding machine and for paying out the wire as it moves from the machine. This is accomplished in this device by means of the spring pressed lever 26 which moves back and forth as shown in Fig. 1, to maintain 70 a substantially constant tension on the wire 19. Whenever its inward movement brings the lever end 26^a into contact with the lever 29, the latter is depressed against the action of the spring 29^a thereby slightly 75 releasing the brake shoe 32 from the brake drum 13, when the tension of the wire 19 will cause the spool 18 to feed out wire until the lever arm 26 moves outwardly 80 sufficiently to release the lever 29 and again 85 permit the spring 29^a to set the brake shoe 32 on the brake drum 13.

Thus as the lever arm 26 moves back and forth, no wire will be fed over the spool 18 until the lever arm 26^a is drawn down so 85 as to engage the lever arm 29 and then only sufficient to permit the arm 26 to move back to a point where the lever 29 is no longer depressed when the spool is again held stationary by means of the brake. 90

A trip 33 is hingedly mounted at 34 and has a finger 35 which is adapted to engage the end of the lever 26^a when the latter swings out too far as when the wire 19 breaks. When this happens, the trip 33 is 95 raised, stopping the braiding machine in a well known manner.

While I have shown and described certain embodiments of my invention, it is to be understood that it is capable of many modifications. Changes therefore in the construction and arrangement may be made without departing from the spirit and scope of the invention as disclosed in the appended claims, in which it is my intention to claim 100 all novelty inherent in my invention as broadly as possible in view of the prior art. 105

I claim:

1. In a braider, a carrier comprising a 110 base, means for rotatably supporting a spool

thereon, a brake drum operably connected to the spool, two spaced members over which the wire from the spool passes, a lever arm pivotally mounted below the level of the center of said spool, a sheave carried thereby and movable toward and from said members, the loop of wire between said members passing over said sheave, a spring urging said sheave away from said members, and means operable by said lever arm as it approaches said members for releasing said brake.

2. In a braider, a carrier comprising a base, means for rotatably supporting a spool thereon, a brake drum operably connected to the spool, two spaced members over which the wire from the spool passes, a lever arm, a sheave carried thereby and movable toward and from said members, the loop of wire between said members passing over said sheave, a spring urging said sheave away from said members, said spring being applied on said lever at a point near its fulcrum, and means operable by said lever arm as it approaches said members for releasing said brake.

3. In a braider, a carrier comprising a base, means for rotatably supporting a spool

thereon, a brake drum operably connected to the spool, two spaced members over which the wire from the spool passes, a lever arm, a sheave carried thereby and movable toward and from said members, the loop of wire between said members passing over said sheave, a spring urging said sheave away from said members, said spring being applied on said lever at a point near its fulcrum, means operable by said lever arm as it approaches said members for releasing said brake, and a trip means operable by said lever arm when it reaches a predetermined point in its outer swing.

4. In a braider, a carrier comprising a base, means for rotatably supporting a spool thereon, a brake drum operably connected to the spool, two spaced members over which the wire from the spool passes, a lever arm, a sheave carried thereby and movable toward and from said members, the loop of wire between said members passing over said sheave, a spring urging said sheave away from said members, and means operable by an end integral with the lever for releasing the brake, as said lever approaches said members.

ARTHUR C. HOPKINS.
